UNITED STATES PATENT OFFICE.

VINCENT O'DONNELLY, OF HOUSTON, TEXAS.

COLOR-SLIDE-OPERATING MECHANISM.

Application filed November 29, 1924. Serial No. 752,921.

This invention relates to new and useful improvements in color slide operating mechanism.

One object of the invention is to provide a mechanism for operating color slides used in grading and testing oil.

Another object of the invention is to provide a mechanism for operating the color slides in grading oil whereby the slides will be protected and kept clean and may be used without liability of breakage and whereby much time may be saved in the testing operation.

With the above and other objects in view this invention has particular relation to certain novel features of construction, operation and arrangement of parts, an example of which is given in this specification and illustrated in the accompanying drawings, wherein:

Figure 1 shows a side elevation of the device.

Figure 2 shows a vertical sectional view.

Figure 3 shows a horizontal sectional view taken on the line 3—3 of Figure 2, and

Figure 4 shows a horizontal sectional view taken on the line 4—4 of Figure 1.

Referring now more particularly to the drawings, wherein like numerals of reference designate similar parts in each of the figures, the numeral 1 designates the housing of the mechanism, which is extended laterally at the bottom, as at 2.

Within the upper part of the housing there is a narrow, oblong, casing 3, provided with any number of pairs of vertical channels 4, separated by partitions 5. The ends of the casing 3, as well as the partitions 5, have aligned rectangular openings 6.

Color slides, as 7, move in the respective channels 4. Each slide is pivoted to the upper end of an operating rod 8. This rod works loosely through bearing slots 9 in the transverse platform 10 secured in the housing. Above this platform each rod carries an annular stop 11, adapted to limit the downward movement of the rods by engagement with said platform 10. Spaced beneath the platform each rod 8 has a fixed seat 12 on which are seated the coil springs 13 which surround said rods and whose upper ends support the slidable stops 14 adapted to engage against the under side of the platform 10. The lower end of each rod 8 is pivoted to the inner end of a lever 15, said levers being pivoted on the transverse rods

16, and pivoted to the outer ends of the levers 15 are the operating keys 17 which work up through corresponding slots in the extension 2. These keys may be numbered to correspond with the numbers of the corresponding slides 7. When a key is depressed the corresponding slide 7 will be elevated into alignment with the openings 6. Each key has a lateral notch forming a shoulder 18 which may be engaged with the end of the corresponding slot, by moving the key laterally, and the corresponding slide thus locked in elevated position, with its corresponding spring 13 under compression. When the key is released said spring will lower the elevated slide until the corresponding stop 11 contacts with the platform 10.

Fitted snugly over the top of the housing there is a hood 19, preferably of sheet metal, to protect the slides from dirt or oil, and having end openings which align with openings 5 and 6. At one end of the hood 19 and offset from said hood, at one side, and formed integrally therewith, there is an eyepiece hood 20, having a rectangular opening 21. Behind the eyepiece hood 20, and alongside the hood 19 there is a platform 22. This platform is provided for the purpose of supporting the cells of oil to be tested. These cells are merely oil containers, open at the top and having transparent ends and are filled with a sample of the oil to be graded, or tested, and are placed one at a time, on the platform 22 for the test.

Extending out beyond the hoods 19 and 20 is a support 23, for the eye piece 24. This eyepiece will usually be the conventional Lovibond eye piece now in common use. It has the sight opening 25, in its outer end, and is separated by the lengthwise, central, vertical partition 26.

Sometimes two, or more of the test slides are elevated into registration in order to exactly match, in color, the oil being tested. The oil thus tested is then given a number equal to the sum of the numbers of the test slides used in making the test.

The cell of oil to be tested is placed on the platform 22 and the test slides 7 are elevated one at a time, and inspected through the eye piece, until a slide is found which corresponds to the color of the oil in the cell under test. The oil tested is then given the number of the corresponding color slide and its grade is thus fixed.

What I claim is:—

1. A device of the character described including an upright housing, an oblong casing at the top of the housing, translucent color slides in said casing and vertically movable into upper and lower positions, a supporting platform for a test cell alongside said casing, means for manually moving each slide into upper position alongside said cell, means for locking each slide in said upper position, yieldable means for moving each slide into lower position when said locking means is released and an eye piece having a single sight opening through which said cell and the associated slide may be simultaneously inspected.

2. A device of the character described including an upright housing, an oblong casing at the top of the housing provided with a plurality of pairs of vertical tracks, a translucent color slide movable in each pair of tracks into upper or lower position, a supporting platform for a test cell alongside said casing, means for manually moving each slide into upper position alongside said cell, means for locking each slide in said upper position, yieldable means for moving each slide into lower position when said locking means is released and an eye-piece having a single sight opening through which said cell and the associated slide may be simultaneously inspected.

3. A device of the character described including an upright housing whose lower end is extended laterally, an oblong casing at the top of the housing provided with a plurality of pairs of vertical channels, partitions separating said pairs, the ends of said casing and said partitions having openings, said openings being in alignment, a color slide movable in each pair of channels, into upper or lower position, operating rods in said

housing pivoted at their upper ends to the respective slides, bearings in the housing through which the respective rods work, a stop on each rod above said bearing adapted to limit the downward movement of said rod, yieldable members surrounding the respective rods, a seat on each rod beneath its bearings, said yieldable members being interposed between said seats and the corresponding bearings, levers pivoted in said laterally extended portion of the housing, each connected at one end to the lower ends of the respective rods, operating keys pivoted to the other ends of said levers, the upper part of said lateral extension having slots through which said keys work, a specimen supporting platform at the top of the housing alongside said slides and an eye piece at the top of the housing having a lengthwise central vertical partition and a sight opening at its outer end through which said slides, when elevated, and the specimen to be tested on said platform may be simultaneously inspected.

4. A device of the character described including an upright housing, an oblong casing at the top of the housing, translucent color slides in said casing and vertically movable into upper and lower positions, a supporting platform for a test cell alongside said casing, means for manually moving each slide into upper position, alongside said cell, means for locking each slide in said upper position and an eye piece having a single sight opening through which said cell and the associated slide may be simultaneously inspected.

In testimony whereof I have signed my name to this specification.

VINCENT O'DONNELLY.
